UNITED STATES PATENT OFFICE.

THOMAS FARMER, JR., OF NEW YORK, N. Y., ASSIGNOR TO CONSOLIDATED CAR-HEATING COMPANY, A CORPORATION OF WEST VIRGINIA.

CAR-DOOR CONTROL.

1,216,300.

Specification of Letters Patent. Patented Feb. 20, 1917.

Application filed February 13, 1913. Serial No. 748,122.

To all whom it may concern:

Be it known that I, THOMAS FARMER, Jr., a citizen of the United States, residing at New York city, borough of Manhattan, county and State of New York, have invented certain new and useful Improvements in Car-Door Control, the following being a full, clear, and exact disclosure of the one form of my invention which I at present 10 deem preferable.

For a detailed description of the present form of my invention, reference may be had to the following specification and to the accompanying drawings, which illustrate my 15 invention, wherein,

Figure 1 shows my invention diagrammatically;

Fig. 2 is a detail sectional view of the air valve.

My invention relates to the control of car doors and resides primarily in a system of door-operating motors which depend upon the motion of the car, being inoperative to open the doors until the car comes to a standstill, regardless of the movement of the car motor controller to its "off" or stopping position. To this end I place a sensitive electromagnet in a shunt circuit across the terminals of the car-propelling motor, whenever the car is about to stop, which magnet serves to keep the door motors disabled, so long as the car is moving. The armature of the car-propelling motor, being geared to the car axle, will continue to rotate so long as the car is in motion and so generate sufficient current in the aforesaid magnet to keep it energized and so in a condition to prevent the operation of the doors until the car comes to a standstill. The circuit of the said 40 magnet (which I will term the disabling magnet) is under the control of the well known "interlock" magnet which serves to give a preliminary ground connection for the "contactor" magnets of the main controller, which ground is broken by the first action of the contactors admitting current to the motor and closed when the controller comes to its "off" position and its contactors are all deenergized. In the said ground connection which the "interlock" establishes I place a pair of contacts controlled by a relay magnet in the ordinary door-signal circuit, those contacts remaining open (and the said ground connection thereby broken) so long 50 as any one of the doors remains open. When

all of the doors are closed the said pair of contacts are also closed and the contactor magnets of the controller receive current and can act to admit current to the propelling motor and regulate its speed in the usual 60 way. This effect, it will be observed, is independent of the motorman's operating handle which may be moved by the motorman in the usual manner to the "on" position to start the car, but the actual starting does not 65 occur until the doors are closed and the contactors receive current as aforesaid. By this arrangement the motorman need pay no attention to the doors but when he is ready to start he will merely turn his handle to the 70 first "on" position in the usual way and the car will start or not according as the doors are all closed or not. If the car does not start at first, it will ultimately start automatically when the doors are all closed and 75 the contactors thereby receive current. Thereafter the doors can not be opened again until the car actually comes to a standstill. The motorman can throw his controller to the "off" position to stop the car but that 80 action will not release the doors and allow them to be opened, since it only serves to bring the said disabling magnet into circuit, which, as I have stated, keeps control of the door motors until the car actually stops. 85 This serves to prevent all on-and-off accidents, since no passenger, nor even the motorman or conductor of the car, can open the doors until the car is at a standstill; nor until all of the doors are closed, will the car 90 start, and not even the motorman can cause the car to start until the doors are actually shut, and when the doors are actually shut the car will start automatically without regard to the motorman, who, however, has 95 indicated his readiness to start by moving his handle to the first "on" position.

Turning to the diagram of Fig. 1, I have omitted therefrom for clearness the controller details which are well known to the 100 art, and require no specific illustration or description.

The circuit X is the ordinary door-signal circuit, having gaps at 1, 2, 3 and 4 which, as is now well known, will be closed automatically by the closure of the respective doors and so, when all the doors are closed, the circuit will be completed from trolley to ground through the signal apparatus a' , and also through a relay magnet a which I 110

place therein for the purpose I have mentioned of dominating the next circuit Y which is the initial ground circuit of the controller and is dominated in turn by the usual "interlock" C, which closes said circuit Y when the controller comes to "off" position and breaks the flow of current to the contactors. It should be borne in mind that the circuit Y is merely one of the "contactor" circuits and, as usual, will contain a contactor magnet, which magnet will control the initial closure of the main motor circuit by which current is first admitted to the motor. The energizing of circuit Y not only admits current to the motor by the main motor circuit but also operates the interlock C to break the ground connection of the said circuit Y through the motor E, it being remembered that the circuit Y contains a high resistance so that while it has a momentary ground connection through the motor yet no material amount of current flows through the motor to said ground by way of the circuit Y. A represents the master controller with its handle which the motorman uses, and B is the contactor box containing the ordinary contactors and contactor magnets which admit current to and regulate the speed of the propelling motor as the master controller may determine. The details of the master controller, the contactors and the circuit connections between the contactors and the propelling motor are not shown herein, since they are well known and form no part of my invention. D is the field magnet and E the armature of the propelling motor.

Coming now to my devices, F represents the disabling magnet aforesaid which is connected, as shown, in a shunt circuit across the terminals of the propelling motor, so long as the interlock at C is closed. The magnet F controls the air supply from the reservoir K to the door motor H that operates the door J. As shown in Fig. 2, the core f' of magnet F, when that magnet is deenergized rests upon the stem of valve f² and, by its weight, unseats the valve against the force of the valve-closing spring, thereby putting the pipes f³ and f⁴ into communication with each other and admitting air pressure from the reservoir K to the reverser-valve G, which, in a manner well known, controls the door motor H when operated in one direction or the other by magnets under control of the respective push-buttons P' and P² in the door-control circuit Z. When said disabling magnet F is energized, it lifts its core f' and thereby allows the valve f² to close and cut off the supply of air from the reservoir to the door motor. The magnet F is a sensitive one and will become energized by the slightest rotation of armature E of the propelling motor or, conversely, will remain energized so long as armature

E is turning, provided that the interlock C is closed to connect the magnet with the motor terminals. When current is admitted to the system by the master controller, the interlock C is opened and magnet F receives current through the circuit Y so long as the circuit remains on, the car being in motion. That will also keep the air supply shut off from the door motors and disable them or render them inoperative. When current is shut off from the system by the master controller and the contactors which it dominates the magnet F will no longer receive current from circuit Y but will receive it from the propelling motor (the interlock being then closed) which acts as a generator so long as it continues to rotate. Not until the propelling motor is at rest will the magnet F become deenergized. In other words the disabling magnet is always in action to disable the door motors except when the car is at rest, and is always receiving current, either from the trolley wire or the propelling motor acting as a generator except when the car is at rest. It acts as a permanent disabling agent for the car door motors, except as it is released by the car coming to rest, so that only when the car is at rest can the doors be operated in either direction.

In the door-signal circuit X is the relay magnet a, which, when energized, closes a pair of contacts in the aforesaid circuit Y. By this means this initial ground circuit Y is controlled by the opening and closing of the doors, as well as by the master switch and, so far as concerns its route through the motors, by the interlock C, the latter being in turn controlled by one of the contactors. If the train is moving, this circuit Y has a ground through the disabling magnet F, the doors being closed, but even if the motorman turns his handle to "off" position, thereby causing the contactor which dominates circuit Y to break the supply of trolley current thereto, it does not affect the disabling magnet, since the interlock closes at the same time and the disabling magnet continues to receive current from the propelling motor acting as a generator and so continues to receive current until the propelling motor stops and the car is at rest. In starting again the motorman pays no attention to the doors but merely turns his handle to the first "on" position which will not start the car but will put the connections in such shape that when the doors are closed, the relay a, being thereby energized, will close the circuit Y and open the interlock C, whereupon the car will start automatically the contactors then receiving current and the disabling magnet being energized by trolley current. The car will then proceed normally with the door motors in disabled condition. The turning of the controller to "off" position will then cut off

trolley current from the propelling motor in the ordinary way and the disabling magnet will continue to receive its current from that motor as above described.

5. What I claim as new and desire to secure by Letters Patent is:

1. The combination with a door, of a motor for operating the same, a source of fluid pressure, means controlling the passage of 10 said fluid pressure from said source to said motor, an electro-magnetic device controlling the passage of said fluid pressure to said controlling means, a circuit for operating said controlling device, said circuit having contacts therein to close the circuit when the door is closed, a manual controller for said circuit, a second circuit for 15 operating said electromagnetic device, and means operating in conjunction with said 20 manual controller for opening either circuit when the other circuit is closed.
2. The combination with a door, of a motor for operating the same, a source of fluid pressure, means controlling the passage of 25 said fluid pressure from said source to said motor, an electro-magnetic device controlling the passage of said fluid pressure to said 30 controlling means, a circuit for operating said controlling device, a second circuit for operating said controlling device, and means operated by the closing of the first circuit for simultaneously opening the second circuit.
3. The combination with a door, of a motor for operating the same, a source of fluid 35 pressure, means controlling the passage of said fluid pressure from said source to said motor, an electro-magnetic device controlling the passage of said fluid pressure to said 40 controlling means, a circuit for operating said controlling device, a second circuit for operating said electro-magnetic controlling device, and an interlock operated by the first circuit and controlling the second circuit.
4. The combination with a door, of a motor for operating the same, a source of fluid 45 pressure, means controlling the passage of said fluid pressure from said source to said motor, an electro-magnetic device controlling the passage of said fluid pressure to said 50 controlling means, a circuit for operating said controlling device, said circuit having contacts therein to close the circuit when the door is closed, a second circuit for operating 55 said electro-magnetic controlling device, and means operated by the closing of the first circuit for simultaneously opening the second circuit.
5. The combination with a car door of an 60 operating motor therefor, a controlling magnet for said motor, a source of current sup-

ply for said magnet containing a contact operated by the door, an alternative source of supply therefor consisting of the car motor acting as a generator and means for shifting 65 the magnet from one source of supply to the other.

6. The combination with a car door of a controlling magnet therefor, a circuit for said magnet including the car motor, a 70 switch in said circuit, a second circuit for connecting the said magnet with a source of supply distinct from said car motor and a contact in said second circuit controlled by the door.

7. The combination with a car door of an operating motor therefor, a source of fluid pressure, means controlling passage of fluid pressure from said source to said motor, a controlling device interposed between said 80 source of pressure and said controlling means, and dependent on the stopping movement of the car, a controlling circuit for the car-propelling motor dependent on the closing of the door and means for rendering said 85 controlling device independent of the car stopping movement when the car-propelling motor is started.

8. The combination with a car door, of an operating motor therefor, a controlling 90 magnet for said motor, means for energizing said magnet from the car motor acting as a generator or from the main current supply, a controlling circuit for the car motor, contacts in series in said controlling circuit operated by a relay in a circuit controlled by 95 the opening and closing of the car door, and means operated by said controlling circuit for shifting the said magnet from one source of supply to the other.

9. The combination with a car door of an operating motor therefor, a source of fluid pressure, means controlling passage of fluid pressure from said source to said motor, a controlling magnet interposed between the 102 source of fluid pressure and said controlling means, two sources of current supply for said magnet, one of which is the car motor acting as a generator, means for starting the car dependent on the closing of the door and shifting devices controlled by said starting means for changing the connection of said magnet from one source of supply to the other.

In witness whereof I have hereunto set 115 my hand, before two subscribing witnesses, this 22nd day of January, 1913.
